C. C. CORY

ILLUMINATING DEVICE

Filed Dec. 27, 1923

Inventor

C. C. Cory

By Watson E. Coleman
Attorney

Patented June 9, 1925.

UNITED STATES PATENT OFFICE.

CHARLES C. CORY, OF SIOUX CITY, IOWA.

ILLUMINATING DEVICE.

Application filed December 27, 1923. Serial No. 683,039.

To all whom it may concern:

Be it known that I, CHARLES C. CORY, a citizen of the United States, residing at Sioux City, in the county of Woodbury and State of Iowa, have invented certain new and useful Improvements in Illuminating Devices, of which the following is a specification, reference being had to the accompanying drawings.

This invention relates to certain improvements in illuminating devices and has relation more particularly to a device of this general character of a decorative type, and it is an object of the invention to provide a novel and improved device of this type embodying a body provided on its periphery with a plurality of reflecting surfaces or facets whereby is produced a device of a highly attractive character and of pronounced aesthetic qualifications.

Another object of the invention is to provide a device of this general character embodying a member provided on its periphery with a plurality of reflecting surfaces or facets, together with means for directing beams of light on such surfaces or facets whereby the device is rendered highly attractive.

The invention consists in the details of construction and in the combination and arrangement of the several parts of my improved illuminating device whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a view partly in section and partly in side elevation and of a diagrammatic character illustrating an illuminating device constructed in accordance with an embodiment of my invention; and

Figure 2 is a view in perspective of one of the reflecting members unapplied.

As disclosed in the accompanying drawings, G denotes a hollow body herein disclosed as of a globular or substantially spherical form, the peripheral wall 1 of said member G being preferably formed of sheet zinc. At diametrically opposed

points, the body G is provided with the internal reinforcing members 2 and 3 providing the radially aligned bearings 4 and 5. 6 denotes an elongated member or shank extending through the bearings 4 and 5, the body G being fixed to the member or shank 6 through the instrumentality of the clamping members 7 herein shown as nuts threaded upon the member or shank 6 at 65 opposite sides of the bearing 4 and in contact therewith. The nuts 7 secure the body G to the member or shank 6 so that, when desired, the member or shank 6 and the body G may be caused to rotate in unison, with 70 the member or shank 6 as the axis of rotation.

In the present embodiment of my invention, the member or shank 6 is vertically disposed and the lower end portion thereof is disposed through the top wall 8 of a hollow base B, said member or shank 6 having associated therewith the bearings 9, preferably of an anti-friction type. Positioned within the hollow base B is a motor M, preferably of an electrical type, which is in driving connection, as at 10, with the member or shank 6 so that, when required, the member or shank 6, together with the body G, may be caused to rotate and particularly when it is desired to materially enhance the aesthetic value of the device in its entirety.

Suitably secured to the periphery of the body G at desired points thereon are the plates 11, preferably mirrors, whereby the periphery of the body G is provided with reflecting surfaces or facets. One of the plates 11 is illustrated unapplied in Figure 2 of the drawings and the outer face thereof is shown as having produced thereon a design a in the nature of a star. It is to be understood that any design may be produced on a plate 11 as preferred, and which design may be a crescent, heart, rose, diamond, or any other fanciful symbol or creation. The design a is preferably produced by applying to the surface of a plate 11 an opaque coating, except at the portions of such surface which produce the required design.

Supported in desired position with respect to the body G are the lamps L so positioned as to direct their beams of light upon the body G from above and at opposite sides thereof so that the resultant reflection from the plates 11 will result in a

highly attractive device possessing æsthetic qualities of the highest type.

From the foregoing description it is thought to be obvious that an illuminating device constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. An illuminating device comprising a hollow base, an upstanding vertically disposed member having its lower portion extending within the base and rotatably supported thereby, means within the base for rotating said member, a substantially globular body fixed to the upper portion of the member, the peripheral wall of said

body being opaque, a plurality of facets secured exteriorly to the peripheral wall of the globular body, said facets being reflective, and lamps supported in a position to direct rays of light upon the globular body from above and at opposite sides thereof.

2. A device of the class described comprising a base, a vertically disposed member rotatably supported by the base, means for rotating the member, a hollow body substantially spherical in form, the peripheral wall of said body being opaque, internal reinforcing members secured to the body at substantially diametrically opposed points, said reinforcing members providing bearings through which the vertically disposed member is directed, means for clamping one of said bearings to the vertically disposed member, the periphery of the spherical body being provided with reflective facets.

In testimony whereof I hereunto affix my signature.

CHARLES C. CORY.
